STOKER CONVEYER

John W. Myers, Roanoke, Va., assignor to The Standard Stoker Company, Incorporated, a corporation of Delaware

Application February 5, 1932, Serial No. 591,124
Renewed August 18, 1934

8 Claims. (Cl. 198—15)

This invention relates to conveying mechanism and more particularly to fuel conveying mechanism for a locomotive stoker whereby fuel is conducted from a source of supply, as from a tender, 5 to the firing opening in the backhead of a locomotive.

It is the general purpose of the invention to provide a novel stoker conveying system that is simple, compact and light in construction, 10 efficient in operation, easily assembled and installed on existing types of locomotives and composed of a minimum number of moving parts.

More specifically it is the purpose of the invention to provide a stoker conveying system 15 comprising a transfer conduit pivotally mounted intermediate its ends on the tender and a riser conduit including telescopically connected sections, one section thereof being rigidly fixed on the locomotive, and the adjacent ends of the 20 transfer and riser conduits being flexibly connected.

Further objects and advantages of the invention will appear from the following description taken in connection with the accompanying 25 drawing, in which

Fig. 1 is a longitudinal, central, vertical section through the rearward portion of a locomotive and the forward portion of a tender, with a stoker in similar section applied thereto; and 30 Fig. 2 is a longitudinal, central vertical sectional view showing a modified form of the invention illustrated in Fig. 1.

In the drawing, the locomotive is represented generally by the letter A, its tender by the letter B, the coupling member joining the locomotive and tender by C and the stoker by D. The locomotive is provided with the firebox 10, the boiler backhead 11 having a firing opening 12 therethrough and the boiler mud ring 13. The 40 tender is provided with the fuel bin 14 having a floor or deck 15 with a longitudinally centrally located aperture 16, and a plurality of slidably mounted plates 17 normally closing the aperture 16 and which may be moved from covering position to regulate the delivery of fuel from the bin.

Movably mounted on the tender is a rigid conduit section designated as a whole by the numeral 18 and which includes the open mouth 50 trough 19, located below the fuel bin 14, the forwardly and slightly upwardly inclined conduit 20 and the interposed enlarged spherical member 21 rigidly secured to each other at their respective adjacent ends in any suitable manner, 55 as for example, by means of bolts passing through

the flanges at their adjacent end. The front wall 22 of the trough 19 is provided with a discharge opening 23. Mounted in the trough 19 and extending forwardly through the opening 23 into the spherical member 21 is a conveyor screw 5 24 for advancing fuel therethrough. The screw 24 is driven from its rearward end in a manner well known in the art and is therefore not particularly illustrated. A conveyor screw 25 is mounted in the conduit 20 and extends into 10 the spherical member 21 where it is connected with the forward end of the conveyor screw 24 by a universal joint 26.

The portion of the stoker mounted on the locomotive includes a riser conduit 27 extending 15 upwardly and forwardly through the locomotive cab deck 28 from a point therebelow to the lower portion of the firing opening 12. The riser conduit 27 comprises an upper section 29 and a lower section 30 telescopically connected. The 20 upper section 29 of the riser conduit 27 is rigidly mounted on the locomotive by suitable means, as by the bracket 31 supporting it from the mud ring 13. The lower end of the lower section 30 of the riser conduit 27 is provided with a spherical split flange 32 arranged to receive the ball 33 at the forward end of the conduit 20 and forming a universal connection therewith. 25

To provide for vertical displacement of the locomotive with respect to the tender and to further provide for relative movement between the locomotive and tender in going around curves, the conduit 18 is mounted intermediate its ends to rotate or pivot about a substantially vertical axis as well as to rock about a substantially horizontal transversely extending axis. 35

For this purpose a bracket 34 is rigidly secured to the trough 19 about midway between its forward and rearward ends. The lower portion of the bracket 34 comprises a horizontally and transversely extending member 35 received in the angle members 36. The angle members 36 which extend forwardly and downwardly for attachment to an adjacent portion of the tender are supported adjacent the bracket 34 by substantially channel shaped members 37. The undersides of the end portions of the member 35 are preferably curved so that the bracket and conduit may rock about a transversely extending horizontal axis. 40

Interposed between the angle members 36 and the channel members 37 is a transversely extending bar 38 which underlies and is adjacent to the member 35 of the bracket. The bar 38 and member 35 are provided with registering 45 50 55

apertures for receiving a vertical pin 39 which, although it enables rotation or pivoting of the conduit 18 about a vertical axis, prevents longitudinal movement thereof. The outer ends of the member 35 are also curved so that when the bracket 34 and conduit 18 rotate about the pivot pin 39 sufficient clearance will be provided between them and the angle members 36.

Located at the upper end of the conduit 27 and disposed in the firing opening 12 is the distributor head 40 and extending forwardly therefrom is the distributor plate 41. The forward wall of the distributor head 40 is provided with a series of jet openings 42 through which pressure fluid, as steam is ejected for impelling fuel over the distributor plate 41. Pressure fluid is admitted to the distributor head 40 through any suitable number of supply pipes 43.

Above the upper end of the conduit 27 is a door frame or casing 44 having top and side portions surrounding corresponding portions of the firing opening, the casing being preferably formed as a separate unit instead of as an integral part of the conduit. Pivoted doors, 45 are provided for closing the rear of the casing 44 and constitute, in effect, a continuation of the rear wall of the conduit 27.

In figure 2 is shown a slightly modified form of the invention differing from the preferred form in that a screw conveyor 46 is mounted in the riser conduit and is universally connected at its lower end to the forward end of the screw 25.

I claim:

1. In a locomotive and tender, a fuel conduit system comprising a tender conduit unit including a rearward conduit section movably mounted intermediate its ends on the tender with reference to movement about vertical and transverse axes, said section being fixed against longitudinal movement, a forwardly extending conduit section rigidly secured to said rearward conduit section, and a locomotive unit including a pair of telescopic sections, one of said telescopic sections being rigidly mounted on the locomotive and the other of said sections being flexibly connected at its rearward end to the forward end of the forwardly extending conduit section of said tender unit.

2. In a locomotive, provided with a firebox having a firing opening, and a tender, a fuel conduit system comprising a tender conduit unit including a rearward conduit section movably mounted intermediate its ends on the tender with reference to movement about vertical and transverse axes, said section being fixed against longitudinal movement, a forwardly extending conduit section communicating with said rearward conduit section, and a locomotive unit including a pair of telescopic sections, one of said telescopic sections being rigidly mounted on the locomotive and communicating with said firing opening and the other of said sections being flexibly connected at its rearward end to the forward end of the forwardly extending conduit section of said tender unit.

3. In a locomotive, provided with a firebox having a firing opening, and a tender, a fuel conduit system comprising a tender conduit unit including a rearward conduit section movably mounted intermediate its ends on the tender with reference to movement about vertical and transverse axes, said section being fixed against longitudinal movement, a forwardly extending conduit section rigidly secured to said rearward conduit section, and a locomotive unit including a

pair of telescopic sections, one of said telescopic sections being rigidly mounted on the locomotive and communicating with said firing opening and the other of said sections being flexibly connected at its rearward end to the forward end of the forwardly extending conduit section of said tender unit.

4. In a locomotive, provided with a backhead having a firing opening therein, and a tender, a fuel conveying system comprising a transfer conduit including a rearward conduit section movably mounted intermediate its ends on the tender with reference to movement about vertical and transverse axes, said section being fixed against longitudinal movement, an upwardly inclined forward conduit section, and a riser conduit including an upper and a lower section telescopically connected, said upper section being rigidly fixed to said backhead and communicating at its upper forward end with said firing opening and said lower section being flexibly connected at its lower rearward end to the forward end of said upwardly inclined forward conduit section, and conveying means for advancing fuel through said conduits.

5. In a locomotive, provided with a backhead having a firing opening therein, and a tender, a fuel conveying system comprising a transfer conduit including a rearward conduit section movably mounted intermediate its ends on the tender with reference to movement about vertical and transverse axes, said section being fixed against longitudinal movement, an upwardly inclined forward conduit section, and a riser conduit including an upper and a lower section telescopically connected, said upper section being rigidly fixed to said backhead and communicating at its upper forward end with said firing opening and said lower section being flexibly connected at its lower rearward end to the forward end of said upwardly inclined forward conduit section, a screw conveyor in said rearward conduit section and a screw conveyor in said upwardly inclined forward conduit section, said screw conveyors being flexibly connected at the junction of said last named conduit sections.

6. In a locomotive, provided with a backhead having a firing opening therein, and a tender, a fuel conveying system comprising a transfer conduit including a rearward conduit section movably mounted intermediate its ends on the tender with reference to movement about vertical and transverse axes, said section being fixed against longitudinal movement, an upwardly inclined forward conduit section, and a riser conduit including an upper and a lower section telescopically connected, said upper section being rigidly fixed to said backhead and communicating at its upper forward end with said firing opening and said lower section being flexibly connected at its lower rearward end to the forward end of said upwardly inclined forward conduit section, and a sectional screw conveyor for advancing fuel through said conduits, said sectional screw conveyor being substantially coextensive with said conduits.

7. In a locomotive, provided with a backhead having a firing opening therein, and a tender, a fuel conveying system comprising a transfer conduit including a rearward conduit section fixedly mounted on the tender with respect to longitudinal movement thereof and pivotally mounted intermediate its ends on the tender about transverse and vertical axes and an upwardly inclined forward conduit section, and a riser conduit in

cluding an upper and a lower section telescopically connected, said upper section being rigidly fixed to said backhead and communicating at its upper forward end with said firing opening and said lower section being flexibly connected at its lower rearward end to the forward end of said upwardly inclined forward conduit section, and conveying means for advancing fuel through said conduits.

10 8. In a locomotive, provided with a backhead having a firing opening therein, and a tender, a fuel conveying system comprising a transfer conduit including a rearward conduit portion movably mounted intermediate its ends on the tender, with reference to movement about vertical

and transverse axes, said section being fixed against longitudinal movement, an upwardly inclined forward conduit portion and an enlarged spherical section interposed therebetween rigidly connecting said rearward and forward conduit portions, and a riser conduit including an upper and a lower section telescopically connected, said upper section being rigidly fixed to said backhead and communicating at its upper forward end with said firing opening and said lower section being flexibly connected at its lower rearward end to the forward end of said upwardly inclined forward conduit section, and screw conveying means for advancing fuel through said conduits.

JOHN W. MYERS.
